US00D450535B1

(12) **United States Design Patent** (10) Patent No.: **US D450,535 S**
 McDonough et al. (45) Date of Patent: **** Nov. 20, 2001**

(54) **TRAINER CUP**

(76) Inventors: **Justin E. McDonough**, 12 Ballentine St., Kenvil, NJ (US) 07847; **Steve Aridgides**, 327 Michael Rd., Yardley, PA (US) 19067

(**) Term: **14 Years**

(21) Appl. No.: **29/141,855**

(22) Filed: **May 14, 2001**

Related U.S. Application Data

(62) Division of application No. 29/116,372, filed on Dec. 30, 1999.

Primary Examiner—M. N. Pandozzi

CLAIM

The ornamental design for trainer cup, as shown and described.

DESCRIPTION

FIG. 1 is a perspective view of a first embodiment of a trainer cup showing our new design;

FIG. 2 is a front elevational view of the first embodiment;

FIG. 3 is a rear elevational view of the first embodiment;

FIG. 4 is a right side elevational view of the first embodiment;

FIG. 5 is a left side elevational view of the first embodiment;

FIG. 6 is a top plan view of the first embodiment;

FIG. 7 is a bottom plan view of the first embodiment;

FIG. 8 is a perspective view of a second embodiment of a trainer cup, having a different cap from the first embodiment;

FIG. 9 is a front elevational view of the second embodiment;

FIG. 10 is a rear elevational view of the second embodiment;

FIG. 11 is a right side elevational view of the second embodiment;

FIG. 12 is a left side elevational view of the second embodiment;

FIG. 13 is a top plan view of the second embodiment; and,

FIG. 14 is a bottom plan view of the second embodiment.
